(57) **CLAIM**

The ornamental design for a chair as shown and described.

DESCRIPTION

1. Chair

Fig. 1.1 is a front view of a chair,

Fig. 1.2 is a top view thereof;

Fig. 1.3 is a left view thereof;

Fig. 1.4 is a right perspective view thereof; and

Fig. 1.5 is a left perspective view thereof.

The design consists of the features of shape and configuration of the entire chair shown in the drawings. The broken lines in the drawings illustrate portions of the chair that form no part of the claimed design.
